Harry C. Schreder
ATTORNEYS.

UNITED STATES PATENT OFFICE.

EARL W. STORMS, OF OAKLAND, CALIFORNIA.

WINDOW FRAME.

Application filed March 21, 1927. Serial No. 177,001.

My invention relates to window frames, and it consists in the combination, construction, and arrangement of parts hereinafter described and claimed.

5 One object of my invention is to so construct a window frame that it is adapted to support a wall structure to which it is fixed. Another object of the invention is to provide a window frame with substantially vertical members which are adapted to hold the 10 balances or pulleys for the window sashes therein so as to dispense with the usual pulley stiles.

An additional object of the invention is to 15 provide a window frame with substantially vertical members of the character mentioned and to join the window sill to the members in such a manner as to make the joints virtually water-tight.

20 A further object of the invention is to construct a window frame so that only a narrow casing is required therefor, both on the inside and on the outside of the wall structure in which the shade is set and that, as a result 25 thereof, the building cost is materially reduced.

Still further objects and advantages will be understood from the following detailed description, illustrated in the accompanying 30 drawings, in which:

Figure 1 is an elevation of one form of window frame constructed according to my invention and set in a wall frame, a portion of which is shown in dotted lines;

35 Figure 2 is a section of the window frame taken in a plane indicated by the line 2—2 in Figure 1 and showing additionally the sash-retaining strips attached to the frame, a portion of the wall-frame structure being indicated by dotted lines;

40 Figure 3 is a section of the window frame taken in a plane indicated by the line 3—3 in Figure 1, the view showing also the sash-retaining strips, and in dotted lines portions 45 of the window sashes and the completed wall structure in which the window frame is set;

45 Figure 4 is an elevation of the lower portion of another form of window frame constructed according to my invention and set in 50 a wall frame, a portion of which is shown in dotted lines;

55 Figure 5 is a section of the window frame taken in a plane indicated by the line 5—5 in Figure 4 and showing also the sash-retaining strips attached to the frame;

Figure 6 is a broken elevation of another

embodiment of my invention, especially adapted for casement window-frame construction, a portion of the wall frame, in which the window frame is set, being indicated by dotted lines; and

60 Figure 7 is an elevation of a portion of the window frame adapted to be set in a masonry wall, the upper portion of the window frame being shown as set in concrete, and the lower portion of the window frame being shown as set in a brick, tile, or stone wall.

65 In the form of my invention, illustrated in Figures 1, 2, and 3, the window frame 1 is set in an opening formed in a wall frame, a portion of which is shown in dotted line. This window frame comprises an upper horizontal member 2, a lower horizontal member 3, inner vertical members 4, which are, at their upper ends, set in grooves formed in the 70 under side of the upper horizontal member 2 and are, at their lower ends, set in grooves formed in the upper side of the lower horizontal member 3, and outer vertical supporting members 5, which are set with their ends 75 in respective recesses formed in the ends of the horizontal members, so that the ends of the horizontal members are flush with the outer side faces of the outer vertical members 5 and that the window frame is thereby 80 adapted to be nailed to the studding of the wall frame.

85 The inner vertical members 4 are provided with obliquely transverse grooves on their inner sides for receiving the ends of a sill 6, so 90 that the sill slopes outward and downward when the window frame is set in the wall structure and so that the sill is supported on the lower horizontal member 3. In the inner vertical members 4 are openings 7 for sash-balancing devices, which are indicated by 95 dotted lines. It is understood, of course, that the openings 7 may be arranged near the top of the window frame for receiving therein the respective pulleys over which run the cords or chains whereby the sashes are connected with the weights therefor. Whether weights or spring balancing-devices are employed, the horizontal members 2 and 3 form pockets 100 with the vertical members for receiving 105 therein the respective balancing devices.

110 Preferably, the inner vertical members 4 are correspondingly rabbeted on both sides, as shown at 9, so that the same member can be used without turning for receiving therein a bead strip 10 between the window sashes, portions of which are indicated by dotted lines

in Figure 3. For the purpose of receiving therein the horizontal bead strip 11, the horizontal member 2 may be similarly rabbeted on both sides, as shown at 12 in Figure 2. When 5 the sashes have been placed in position in the window frame, horizontal and vertical strips 13 and 14, which preferably form parts of the window casing, are suitably secured to the window frame for retaining the sashes therein. In Figure 3 is indicated by dotted lines how toe nails may be driven thru the outer vertical members 5 for securing the window frame 1 to the studding of the wall frame, and in Figure 1 is also indicated by dotted lines 10 how the window frame closely fits under a horizontal member of the wall frame and fits upon supporting studs at the bottom. It is thus seen that the window frame, when in place, aids in supporting the wall structure. 15 After the window frame has been secured in position in the wall frame, the wall is sheathed and plastered in the usual manner, and the casing is fitted, so that the manner in which the window frame is joined to the wall 20 frame is thereby made inconspicuous. 25

The lower portion of a window frame 15, which at its upper portion is similar to the frame 1, already described, is shown in Figures 4 and 5. In this instance, the lower horizontal member 16 of the frame supports thereon at its ends the outer vertical members 17, but the sill 18 extends between the members 17 and is secured thereto and supported on wedges 19, preferably secured in transverse grooves on the upper side of the horizontal member 16, so that the sill thus slopes outward and downward when the window frame is set in the wall frame. Also, in this instance, the inner vertical members 20 are preferably set with their lower ends in transverse grooves cut in the upper side of the sill and spaced from the vertical members 17 correspondingly with the grooves in the horizontal member, so that the members 17 are thereby positioned directly above the respective wedges and are thus supported on the lower horizontal member 16 as effectively as the members 4 in the frame 1, shown in Figure 1, are supported by the lower horizontal member 3. Pockets 21, corresponding to the pockets 8 in the frame 1, are also formed in the frame 15, which is otherwise similar in construction to the frame 1, so that a further description thereof appears unnecessary in order to understand its adaptability of application. 55

In Figure 6 are shown portions of a window frame 22, which is particularly adapted to be used as a casement window-frame, although it 60 may also be used as a frame for sliding sashes. It differs from the frame 15, shown in Figure 4, only in that it has no outer vertical supporting members and in that the window sill 23 extends so as to be with its ends in respective 65 planes with the ends of the upper horizontal

member 24 and the lower horizontal member 25. In this instance, the vertical members 26, which take the place of the inner vertical members 20 in the frame 15 are made heavy so as to be capable of supporting thereon 70 not only the upper horizontal member but also that part of the wall structure which rests upon the horizontal member. It should be observed that, since the ends of the upper horizontal member overhang the ends of the 75 window sill, the vertical members also, in this construction, form pockets 27 with the respective ends of the sill and the upper horizontal member, so that, if it is desired to use the frame 22 for holding sliding sashes therein, the pockets are adapted to receive therein the balancing devices or weights for the sashes. The extension of the upper horizontal member beyond the vertical members also tends to place some of the weight of the superstructure upon the ends of the horizontal member and thereby to counteract any tendency of the horizontal member to sag at its 80 center. 85

The construction of the window frame 28, shown in Figure 7, is virtually the same as that of the frame 22, shown in Figure 6, but, while in the latter figure the dotted lines indicate the setting of the window frame 22 in a wooden-frame wall, Figure 7 shows the frame 90 28 set partly into a concrete wall 29 and partly into a brick, tile, or stone wall 30. In this instance, the vertical members 31 are shown as provided with balancing devices 32, and, in order to reinforce the vertical members so 95 as to compensate for the cut-out portions in which the balances are set, blocks 33, adapted to receive portions of the respective balances therein, are fixed to the vertical members. For the reception of these blocks, pockets 34 are 100 formed similarly to the pockets 27 in the frame 22, but, if spring balances 32, as indicated, are used, the concrete wall 29 and the brick, tile, or stone wall 30 may extend all the 105 way to the vertical members 31 and the 110 wedges 35 so as to embed the ends of the upper horizontal member 36, the sill 37, and the lower horizontal member 38 and thus reduce the size of the pockets in order that the wall 115 formations 29 and 30 at the vertical members 31 of the window frame 28 may assist the frame in supporting the superstructure of the wall. 120

I claim as my invention:

1. A window frame adapted to be set in, 120 and to support, a wall structure, the frame comprising upper and lower substantially horizontal members; wedges secured upon the lower horizontal member and spaced from the ends thereof; a sill secured upon the 125 wedges, and the wedges being so inclined that the sill thereon slopes outward and downward when the frame is set in the wall structure; and substantially vertical members secured at their lower ends upon the sill direct. 130

ly above the respective wedges and joined to the under side of the upper horizontal member, the respective ends of the horizontal member on the sill being substantially in the 5 same plane.

2. A window frame adapted to be set in, and to support, a wall structure, the frame comprising upper and lower substantially horizontal members; wedges secured upon the 10 lower horizontal member and spaced from the ends thereof; a sill secured upon the wedges, and the wedges being so inclined that the sill thereon slopes outward and down-

ward when the frame is set in the wall structure; substantially vertical members secured 15 at their lower ends upon the sill directly above the respective wedges and joined to the under side of the upper horizontal member in a spaced relation to the ends thereof, the vertical members having openings therein for the 20 reception of sash-balancing devices; and reinforcing blocks secured to the respective vertical members at the respective openings.

In testimony whereof I affix my signature.

EARL W. STORMS.
